HIGH-SPEED PLANER

Wolfgang Rossmannith, Solothurn, Switzerland;
vested in the Alien Property CustodianApplication June 19, 1942, Serial No. 447,690
In Germany June 21, 1941

1 Claim. (Cl. 90—38)

The present invention relates to high-speed planers. Planing machines are known where the tool during its whole stroke along its whole length is guided in a guide member rigidly fast to the standard of the machine. Standard and guide member may also be arranged to form a closed frame by means of a support serving also as a guide for the work-table which is adjustable in height. The long continuous guiding means of the tool in combination with the rigid frame permits the use of hard metal tools and thereby a high planing speed. The double mobility of the table laterally and in height leaves in the closed frame a certain flexibility which impairs the exactness of the working of the machine, such that the machine will only be suitable for light and simple work.

In other planing machines with tools likewise guided all along their whole stroke the work-table is stationary. But the tool carrier is made adjustable in height along lateral pillars, which pillars also support its mechanism for securing horizontal movements. The tool travels in an unsupported cross bar of a freely extended and longitudinally adjustable arm. Also this arrangement does not provide the stability which is necessary for advantageously utilizing hard metal tools.

The high-speed planing machine according to the invention is noteworthy for its capacity of resistance, and is adapted to all requirements.

This is obtained by distributing in a particular manner the adjustable means and the working arrangements by employing suitable guide means. According to the invention, the planing tool is guided along its whole stroke and along its whole length upon a support adjustable in height and

the work-table is only utilized for moving the work-piece. A machine of such an arrangement works exactly and cleanly. It is especially suited for heavy work and bulky work-pieces. It may be constructed as a one or a two pillar machine.

The annexed drawing shows by way of example a planing machine according to the present invention diagrammatically in side view.

In the figure, the pillars b and b_1 are located on the two sides of the table a which may execute its feeding movements on the base a_1 at right angles to the plane of the drawing.

The tool carrier c is made adjustable in height along the guides b_2 and b_3 on the pillars b and b_1 . The means c_2 for operating the plane tool d , for instance in a hydraulic manner, are guided on the extended end c_1 of the carrier c , the planing tool being reciprocated by a connecting rod d_1 . By mounting the tool drive entirely on the carrier, which is adjustable vertically, a simple arrangement is attained whereby advantageous performance is secured without complicated driving mechanisms.

What I claim is:

25 In a high-speed planer, a rigid frame comprising a base, a pair of pillars at opposite sides of the base, and a top brace connecting the upper ends of the pillars, a work-table reciprocably mounted on the base, a tool-carrier mounted on the pillars for vertical adjustment relatively to the work-table, and a planing tool including a hydraulic cylinder carried by the tool-carrier, a piston reciprocable in said cylinder, a piston rod, and a cutting member carried by the piston rod, 30 said piston rod and cutting member being guided in their movements on the tool carrier.

WOLFGANG ROSSMANITH.
